UNITED STATES PATENT OFFICE.

OSCAR E. SERVIS, OF CHICAGO, ILLINOIS.

ELECTRODE SUSPENSION DEVICE.

Application filed January 28, 1921. Serial No. 440,716.

To all whom it may concern:

Be it known that I, OSCAR E. SERVIS, a citizen of the United States, residing in Chicago, in the county of Cook and State of Illinois, have invented a new and useful Improvement in Electrode Suspension Devices, of which the following is a specification.

This invention relates to a suspension device for electrodes and has for objects the provision of a suspension device by which electrodes of standard form and construction may be adjustably suspended from the conductor rod into an electrolytic bath, so that the position of the electrode in said bath may be readily adjusted to accommodate varying top levels of the bath and wearing away of the electrode, and also to provide a suspension device constructed to make a sure gripping contact with the conductor rod.

In addition to the general objects recited above, the invention has for further objects such other improvements or advantages in construction and operation as are found to obtain in the structures and devices hereinafter described or claimed.

In the accompanying drawings forming a part of this specification, and showing, a preferred form and manner in which the invention may be embodied and practiced, but without limiting the claimed invention specifically to such illustrative instance or instances:

Figure 1 is an elevational view showing the invention applied to bar anodes of standard type;

Fig. 2 is a detailed vertical section on the line 2—2 of Fig. 1, showing the suspension device in side elevation and its mode of attachment to the conductor rod;

Fig. 3 is a front elevation of the parts illustrated in Fig. 2;

Fig. 4 is a vertical sectional elevation taken in a plane indicated by the line 4—4 of Fig. 3, and

Fig. 5 is a side elevation of a modified form of suspension device.

The device of the present invention is especially constructed for suspending anodes of the standard bar type, and for convenience the present description will be confined to this use of the invention. Features

of construction and operation are, however, adaptable to other valuable applications, for example to anodes of other types and to other electrodes; consequently, the scope of the invention is not confined to the specific use and specific embodiment herein described as an illustrative example.

Referring to the drawing, there is shown at 11 a standard bar anode, said anode embodying in its construction the usual shank 12 of reduced diameter with respect to the main body portion of the anode and by which the anode is suspended from the conductor rod 13 of an electrolytic bath, indicated diagrammatically at 14. Heretofore it has been customary to construct the reduced shank 12 of the anode of ductile and easily bendable metal and to bend said shank 12 into the form of a hook that is hooked over the conductor bar 13 to suspend the anode in the electrolytic bath. This practice is not only clumsy and tedious and admits of no uniformity in the relative positions of several anodes suspended in the bath, but also offers the serious objection that no adjustment of the position of the anode can be made to compensate for varying levels of the top surface of the bath and for wearing away of the anode by electrolytic decomposition.

The present invention provides an exceedingly simple and effective suspension device for electrodes of this nature which is especially adaptable for use in connection with anodes of the standard bar construction described above and not only provides for the secure suspension of such anodes in an electrolytic bath without any departure whatever in the construction of the anodes themselves, but also has the additional advantage of permitting the anode to be adjusted vertically relatively to the suspension device so as to admit of absolute regulation of the height of the anode in the electrolytic bath.

As shown in Figs. 1 to 4 inclusive of the drawing, the improved suspension device of the present invention embodies in its construction a sleeve member 15 from the upper end of which extends a curved bar member 16 that is bent downwardly at its top to form a hook 17. The sleeve member 15 of the suspension device is provided with a

socket 18 extending longitudinally of the axis of said sleeve member 15 and adapted to receive the standard shank 12 of an anode 11, as shown. Extending inwardly from one side of the sleeve member 15 are two set screws 19 which may be respectively screwed into the socket 18 to grip the shank 12 of an anode inserted into said socket 18 and thereby to hold the anode shank securely in said socket. A curved leaf spring 20 provided with a slot 21 is secured against the inner face of the bar member 16 by means of a set screw 22 passed through the slot 21 of the spring and screwed into a threaded socket 23 in the aforesaid bar member. At its upper end the spring 20 is formed with a downwardly bent portion 24 adapted to engage a portion of the circumference of the conductor rod 13 and hold the suspension device rigidly on the conductor rod.

In utilizing the suspension device of the invention, the two set screws 19 are loosened and the electrode shank 12 is inserted into the socket 18 of the suspension device. When the proper relative positions of electrode and suspension device have been attained, the set screws 19 are tightened to secure the electrode to the suspension device. The electrode may then be readily suspended from a conductor rod, such as indicated at 13, by hanging the hook 17 at the top of the suspension device on the conductor rod. In practice the spring 21, as well as the hook portion and sleeve portions of the suspension device will be made of conducting material, and when the suspension device has been applied to the conductor rod, a three point conducting contact with such rod will be made, thereby insuring passage of the current into the body of the electrode. The small spring construction combined with the hook formation of the suspension device secures a rigid suspension from the conductor rod and prevents wabbling of the electrode in the bath.

In the form of the invention illustrated in Fig. 5 the upper end of the rod portion 16 of the suspension device is provided with a hooklike member 25 bent oppositely from the hook 17. This member 25 is of particular value when the suspension device is applied to a cathode tray, for the purpose of lifting the articles supported by said tray from the electrolytic bath. The suspension device shown in Fig. 5 is moreover provided with only one set screw 19 for gripping the shank of the electrode instead of the two set screws illustrated in the other figures. Except as herein mentioned, the construction and operation of the device illustrated in Fig. 5 is the same as that of the other figures.

The invention as hereinabove set forth is embodied in a particular form of construc-

tion, but may be variously embodied within the scope of the claims hereinafter made.

I claim:

1. The combination with an electrode having a suspension shank, of a suspension device therefor, comprising: a sleeve member having a socket for receiving the electrode shank, means carried by said sleeve member for engaging a shank inserted in said socket to secure the shank to said sleeve member, a hook extending from one end of said sleeve member and adapted to be hooked over and to engage two circumferential portions of a conductor rod, and a spring adjustably secured to the hook portion of said suspension device and adapted to engage with a yielding pressure a third circumferential portion of the conductor rod; substantially as specified.

2. The combination with an electrode having a suspension shank, of a suspension device therefor, comprising: a sleeve member having a socket for receiving the electrode shank, means carried by said sleeve member for engaging a shank inserted in said socket to secure the shank to said sleeve member, a hook extending from one end of said sleeve member and adapted to be hooked over and to engage two circumferential portions of a conductor rod, and spring means carried by said suspension device and adapted to engage a third circumferential portion of the conductor rod; substantially as specified.

3. The combination of an electrode provided with a vertical rod by which it may be suspended, of an adjustable hook device for said electrode including a sleeve for slidably embracing said rod and means for holding said sleeve in adjusted position with respect to said rod; substantially as specified.

4. A suspension device for electrodes, comprising: a sleeve member having a socket for receiving the electrode shank, means carried by said sleeve member for engaging a shank inserted in said socket to secure the shank to said sleeve member, a hook extending from one end of said sleeve member and adapted to be hooked over and to engage two circumferential portions of a conductor rod, and a spring adjustably secured to the hook portion of said suspension device and adapted to engage with a yielding pressure a third circumferential portion of the conductor rod; substantially as specified.

5. A suspension device for electrodes comprising: a sleeve member having a socket for receiving the electrode shank, means carried by said sleeve member for engaging a shank inserted in said socket to secure the shank to said sleeve member, a hook extending from one end of said sleeve member and adapted to be hooked over and to engage two circumferential portions of a conductor

rod, and spring means carried by the suspension device and adapted to engage a third circumferential portion of the conductor rod; substantially as specified.

6. A suspension hook device for electrodes comprising: a hook member adapted to be suspended from a conductor rod and pro-

vided with a sleeve for slidably embracing the vertical rod of an electrode, and means for holding said sleeve in adjusted position with respect to the electrode rod; substantially as specified.

OSCAR E. SERVIS.
